SHOE SOLE

Masanobu Inohara, 530-1 Sawada, Kamioka-cho,
Tatsuno, Hyogo, Japan

Continuation-in-part of abandoned design application Ser.
No. 313,519, Dec. 8, 1972. This application Mar. 21,
1974, Ser. No. 453,557

Term of patent 14 years

Int. Cl. D2—04

U.S. Cl. D2—320

FIG. 1

FIG. 2

FIG. 3

FIG. 4

FIG. 5

FIG. 1 is a bottom plan view of a shoe sole showing my new design;

FIG. 2 is a side elevational view thereof;

FIG. 3 is an elevational view of the other side;

FIG. 4 is an enlarged cross sectional view; and

FIG. 5 is an enlarged fragmentary bottom plan view.

The characteristic feature of the design resides in the appearance of the sole and the upper in which the sole extends generally vertically upwardly a substantial distance above the bottom of the sole around the entire periphery of the upper, the vertical extent of the sole being greatest at the side opposite the instep portion of the upper, the design of the vertically extending portion of the sole being continuous with the design of the bottom of the sole and having cylindrical projections surrounded by interconnecting hexagonal walls.

This is a continuation-in-part of copending application Ser. No. 313,519, filed Dec. 8, 1972, and now abandoned.

I claim:
The design for a shoe sole, as shown and described.
